FOLDING ROCKING CHAIR

Edward Gingerich and Edna S. Gingerich, De Queen, Ark.

Application July 8, 1957, Serial No. 46,862

Term of patent 14 years

(Cl. D15—6)

FIG. 1.

FIG. 2.

FIG. 3.

Figure 1 is a side elevational view of a folding rocking chair embodying my new design in normal rocking position;

Figure 2 is a larger scale perspective view of my design in partially collapsed position; and

We claim:

The ornamental design for a folding rocking chair, substantially as shown.
